W. P. MANUEL,
ATTACHMENT FOR PENCILS.
APPLICATION FILED MAR. 10, 1917.

1,236,331.

Patented Aug. 7, 1917.

Inventor:
William P. Manuel
by *Edmund G. Strauss, Atty.*

UNITED STATES PATENT OFFICE.

WILLIAM P. MANUEL, OF LOS ANGELES, CALIFORNIA.

ATTACHMENT FOR PENCILS.

1,236,331.

Specification of Letters Patent. Patented Aug. 7, 1917.

Application filed March 10, 1917. Serial No. 153,853.

To all whom it may concern:

Be it known that I, WILLIAM P. MANUEL, a subject of the King of Roumania, residing at Los Angeles, in the county of Los Angeles and State of California, have invented new and useful Improvements in Attachments for Pencils, of which the following is a specification.

This device relates to an attachment for 10 pencils arranged for adjustably feeding an eraser, or like article as the latter is worn, and decreases in length.

It is an object of this invention to provide an attachment having a barrel for 15 carrying a calendar or other display sheet and within which is disposed a structure for adjustably feeding an eraser.

It is another object to provide details of construction whereby a compact feeding 20 structure is obtained, and whereby the eraser or like article may be quickly and conveniently renewed.

It is a further object to provide an attachment for a pencil, having a pocket retaining 25 means to prevent loss of the pencil, a calendar and an eraser holder which is compact, light, easily attached and pleasing in appearance.

I accomplish these objects by means of 30 the embodiment of my invention illustrated in the accompanying drawing, in which:

Figure 1 is an elevation of the pencil with my attachment applied thereto.

Fig. 2 is an enlarged vertical section 35 through the attachment as seen on the line 2-2 of Fig. 1, the eraser being shown in its innermost position.

Fig. 3 is a fragmentary sectional view 40 similar to Fig. 2 showing the eraser projected.

Fig. 4 is a section as seen on the line 4-4 of Fig. 2.

Fig. 5 is a section as seen on the line 5-5 of Fig. 2, and

Fig. 6 is a section as seen on the line 6-6 of Fig. 2.

As it will be noted from an inspection of Fig. 1, the attachment A is placed on the end of a pencil B in the manner in which the 50 ordinary pocket clips are placed upon the pencils. The attachment A is comprised of a shell having a sleeve 7 for engagement with the pencil B, and an enlarged barrel to receive a calendar. The barrel is of tubular form and is provided with cut out portions leaving openings for the display of

calendars. The barrel, therefore, comprises an upper cylindrical ring 8 and a lower ring 9 joined by columns, which are indicated by 10. The upper ring 8 is split as shown in 60 Fig. 5 so that it is expansible.

The sleeve 7 is split longitudinally, as indicated by 11 and is provided with an intersecting slit 12 thereby providing spring fingers for gripping the end of the pencil. Secured to sleeve 7 and preferably integral therewith is a depending clip 13 having a ball 14 at the end thereof. The clip is for the purpose of securing the pencil in the pocket and retaining it against loss. 65 70

Secured to the shell and disposed within the calendar barrel is a post 15. Post 15 is hexagonal in cross section for the purpose of providing flat sides.

Ring 9 has an off-set formed therein as indicated in Fig. 2 to provide a rabbet in which a calendar sheet indicated by the dotted lines may be disposed. The upper ring 8 is indented to provide a rabbet and also has an indentation to receive a raised 80 portion on the interior of a cap. The post 10 is also indented to provide rabbets. The structure of the barrel is such that calendar sheets, preferably inclosed in a transparent stiff material, such as celluloid, may be disposed in the openings between the columns. The rabbets will prevent rotation of the 85 calendars. Any other display sheet may be used instead of a calendar.

Mounted upon post 15 is an eraser holder 90 consisting of a sleeve 16 having a hexagonal bore to prevent rotation, and having external threads upon the lower end of its periphery. The upper end is reduced in diameter and slit to provide gripping jaws for 95 engaging and retaining an eraser 17. It will be noted that the eraser may be slipped between the jaws and removed by pulling it therefrom. The jaws bite the eraser with sufficient force to hold it in place for the 100 ordinary strain to which it is subjected in erasing.

Mounted upon the barrel is a cap. The cap is comprised of a cover 18 having a neck through which the eraser may be projected. An apron 19 overhangs the ring 8. The apron is provided with a raised rib 20 on its interior which engages with the indentation in the ring 8. It is obvious that by pressing the cap 18 into place and contracting the 110 ring 8 by pressing upon the same, the cap will reach its locking position, and upon re-

lease of the pressure upon ring 8 the latter will expand the indentation and rib locking to prevent the displacement of the cap from the barrel. To remove the cap the ring 8 is contracted; pressing upon the columns 10 will cause contraction of the ring. The cap may then be withdrawn from the barrel.

Depending from the cover is a sleeve 21. Sleeve 21 is provided internally with threads 10 at its lower end which engage with the threads on holder 16. It is obvious that the cap may be rotated upon the barrel and that the rotation of the cap sleeve 21 will force the holder 16 upwardly or downwardly at 15 will as the holder cannot rotate, being held in position by the post 15. The holder is, thus, projected and the eraser forced through the cover. The holder and eraser in their upper position are shown in Fig. 3.

20 In order to provide convenient gripping means to rotate the cap, the outer surface of the apron is knurled. The pencil B may be forced into the attachment with the upper end thereof extending within the post 25 thereby providing for secure attachment to the pencil.

What I claim is:

1. An attachment for pencils comprising a shell, a post disposed within and fixed 30 to said shell; a holder mounted on said post for axial sliding movement and held against rotation, said holder provided at its free end with gripping jaws and at the other end with an external thread; and a rotatable 35 sleeve disposed within said shell and held against axial movement, said sleeve provided with internal threads engaged with the threads on said holder for moving the holder axially of said shell.

40 2. An attachment for pencils, comprising a shell having a sleeve adapted to engage a pencil, said shell having a calendar barrel and provided with a hollow post disposed within said barrel adapted to receive the 45 end of a pencil; an eraser holder mounted on said post for axial sliding movement and held against rotation, said holder provided at the upper end with gripping jaws; and a cap for said shell having an opening for 50 an eraser to be projected therethrough and a depending sleeve having a screw engaging it with said holder so that upon rotation of said holder the latter will be moved axially.

55 3. An attachment for pencils, comprising a shell having a sleeve adapted to engage a pencil, said shell having a barrel adapted to carry a calendar and provided with a hollow post disposed within said barrel 60 adapted to receive the end of a pencil; an eraser holder mounted on said post for axial sliding movement and held against rotation; said holder provided at the upper end with gripping jaws; and a cap for said 65 shell having an apron overhanging the up-

per end of said shell and engaged by catch means therewith; an opening in said shell having an eraser to be projected therethrough, and a depending sleeve having a screw engaging it with said holder so that 70 upon rotation of said sleeve the holder will be projected.

4. An attachment for pencils, comprising a shell having a sleeve adapted to engage a pencil, said shell having an enlarged portion 75 adapted to carry a calendar and provided with a hollow post disposed within said enlarged portion adapted to receive the end of a pencil; an eraser holder mounted on said post for axial sliding movement and held against rotation, said holder provided at the lower end with an external thread and at the upper end with gripping jaws, and a cap for said shell having an apron overhanging the upper edge of said shell, 80 an opening for an eraser to be projected therethrough, and a depending sleeve provided with internal threads engaged with the threads on said holder.

5. An attachment for pencils, comprising 90 a shell having a sleeve adapted to engage a pencil, said shell having an enlarged portion adapted to carry a calendar and provided with a hollow post disposed within 95 said enlarged portion adapted to receive the end of a pencil; an eraser holder mounted on said post for axial sliding movement and held against rotation, said holder provided at the lower end with an external thread and at the upper end with gripping jaws; 100 a cap for said shell having an apron overhanging the upper edge of said shell, an opening for an eraser to be projected therethrough, and a depending sleeve provided with internal threads engaged with the threads on said eraser holder, said apron provided with catch means to lock it to said shell against axial displacement.

6. An attachment for pencils, comprising 110 a shell having a sleeve adapted to engage a pencil, said shell having an enlarged portion adapted to carry a calendar, the upper peripheral edge of said shell being split, said shell being provided with a hollow post disposed within said enlarged portion and 115 adapted to receive the end of a pencil; an eraser holder mounted on said post for axial sliding movement and held against rotation, said holder provided at the lower end with an external thread and at the upper end with gripping jaws; and a cap for 120 said shell having an apron overhanging the upper edge of said shell, an opening for an eraser to be projected therethrough, and a depending sleeve provided with internal threads engaged with the threads on said eraser holder, said apron provided with 125 catch means to lock it about said upper edge of the shell.

7. An attachment for pencils, comprising 130

a shell having a sleeve adapted to engage a pencil, said shell having an enlarged portion adapted to carry a calendar and provided with a flattened hollow post disposed within said enlarged portion adapted to receive the end of a pencil; an eraser holder mounted on said post for axial sliding movement and held against rotation, said holder provided at the lower end with an external 15 thread and at the upper end with gripping

jaws; and a cap for said shell having an apron overhanging the upper edge of said shell, an opening for an eraser to be projected therethrough, and a depending sleeve provided with internal threads engaged with the threads on said holder.

In witness that I claim the foregoing I have hereunto subscribed my name this 28th day of February, 1917.

WILLIAM P. MANUEL.
